GARMENT HANGER

Benjamin Zuckerman, New York, N.Y., assignor to Mister Hanger, Inc., New York, N.Y., a corporation of New York

Filed Mar. 8, 1965, Ser. No. 84,152

Term of patent 3½ years

(Cl. D80—8)

FIG. 1 is an elevational view taken from one side of a garment hanger showing my new design, the opposite side being a mirror image of the side shown,

FIGURE 2 is a sectional view taken along line 2—2 of FIGURE 1,

FIGURE 3 is a sectional view taken along line 3—3 of FIGURE 1,

FIGURE 4 is a vertical sectional view of one arm of the hanger taken along line 4—4 of FIGURE 1, and

FIGURE 5 is a sectional view of the ribbed slot taken along 5—5 of FIGURE 1.

The essential feature of the subject invention resides in the design and configuration of the lower portion of the laterally extending transverse shoulders or arms. That is, the design and disposition of the slots at the bottom of the arms at the outer extremities thereof. Further, the design and disposition of the ribbed portion surrounding the slot as well as the bead at the end of the slot.

I claim:

The ornamental design for a garment hanger, as shown and described.
